UNITED STATES PATENT OFFICE.

EDWARD PASCOE, OF SIOUX CITY, IOWA.

SAFE-DOOR.

No. 853,825.

Specification of Letters Patent.

Patented May 14, 1907.

Application filed July 3, 1906. Serial No. 324,648.

To all whom it may concern:

Be it known that I, EDWARD PASCOE, a citizen of the United States, residing at Sioux City, in the county of Woodbury and State 5 of Iowa, have invented new and useful Improvements in Safe-Doors, of which the following is a specification.

This invention relates to safe doors, the object of the invention being to provide means 10 for securing and locking the doors of safes, whereby the same are rendered more secure and effective against burglars, an effective interlocked engagement being obtained between the door and the body of the safe inde- 15 pendent of the ordinary locking means.

With the above general object in view, the invention consists in the novel construction, combination and arrangement of parts hereinafter more fully described, illustrated and 20 claimed.

In the accompanying drawings, Figure 1 is a front elevation of a safe, showing the door thereof embodying the present invention, closed. Fig. 2 is a similar view, showing the 25 door open in edge view. Fig. 3 is a front elevation of the safe, showing the door thrown all the way open and illustrating the manner of mounting the door. Fig. 4 is a sectional plan view, showing the mechanism for im- 30 parting a partial rotary movement to the door. Fig. 5 is a vertical sectional view of a portion of said mechanism. Fig. 6 is a detail elevation of the worm, showing the reversible ratchet.

Referring to the drawings, 1 designates a safe of any desired size and general construction, 2 representing the front wall of the safe, the same being provided with the doorway or opening 3, the said opening being preferably 35 round, while 4 designates the door which is also round and beveled on its outer periphery or rim and adapted to fit snugly into the doorway or opening 3 in the manner illustrated in Fig. 1.

In carrying out the present invention, the door 4 is centrally journaled and adapted to turn on a center bolt or pin 5 which is carried by a hinged door supporting arm 6, the latter being bifurcated and the branches thereof 50 being hinged at 7 to the body of the safe, as shown in Figs. 1 and 3. It is to be understood that the door 4 is journaled directly on the bolt or pin 5 and that the latter is carried by the projecting end or portion of the hinged arm 6.

The door 4 is provided on its outer periph-

ery or rim with mutilated or interrupted screw threads, or in other words, the said rim is provided with threaded segments 8 of any suitable length and intervening spaces or 60 blanks 9 which are left unthreaded. The circular wall which bounds the opening 3 is provided with corresponding threaded segments 10 and also with corresponding intervening spaces 11 and the threaded segments 65 8 and 10 of the door and doorway are arranged alternately so that as the door is closed and opened, the threaded segments of the door enter the unthreaded spaces 11 of the doorway, while the threaded segments 10 70 of the doorway fit into the unthreaded spaces 9 of the door.

Under the preferred embodiment of this invention, the threaded segments on the door and in the doorway are of equal length circumferentially of the opening and the length of the intervening spaces 9 and 11 are also of a length equal to the length of the threaded segments. Therefore, when the door is shut and partially turned on the axis bolt or pin 5, 80 the threaded segments of the door and doorway are moved into engagement with each other and in such turning of the door, said threaded segments interlock and crowd the door inward with a tight fit into the door 85 opening. The door is also shouldered to receive a gasket 12 which finds a seat or bearing against a corresponding shoulder 13 in the doorway, thus giving a practically airtight and fire-tight fit. 90

The mechanism for imparting a partial revolution to the door 4 embodies a worm segment 14 secured to the door and having the teeth 15 thereof projecting slightly beyond the periphery of the door, as shown in 95 Figs. 1, 3 and 4. Meshing with the segment 14 is a worm 16 which is journaled on a vertical axis and mounted on the front of the safe by means of a bracket 17 secured rigidly to the safe. The worm 16 is journaled at 100 its upper end in said bracket and also carries a ratchet wheel 18 fast thereon, which ratchet wheel is engaged by a dog 19 pivotally mounted on the shorter arm 20 of a hand-lever 21 which is fulcrumed at 22 on 105 the elbow 23 of a fulcrum pin 24 which extends downward through the projecting portion of the bracket 17 through the ratchet wheel 18 into the worm 16, as clearly shown in Fig. 5, the fulcrum pin 24 being loose in 110 the wheel 18 and worm 16. The dog 19 is double-ended or provided with two engag-

ing points as shown in Fig. 6 and also with a projecting shank 25 which extends upward and is engaged by a spring 26 also carried by the short arm 20 of the lever 21, said 5 spring acting on the shank of the dog to hold either engaging point thereof in engagement with the teeth of the ratchet wheel 18, according to the direction in which it is desired to turn the worm and revolve the safe 10 door.

After the door has been closed by means of the ordinary handle 27, the handle 21 is raised from the vertical position indicated by dotted lines in Fig. 5 to the horizontal position indicated by full lines in the same figure, and the dog 19 having been set at the proper angle, the lever 21 is swung horizontally, whereupon the dog 19 engages the ratchet wheel 18 and turns the worm 16 which in turn 15 engages the worm segment 14 and turns the door on its pivot 5 far enough to move the threaded segments of the door into interlocked engagement with the threaded segments in the doorway. The safe door may then be locked 20 by means of any type of lock usually employed.

In order to open the safe door, after the same has been unlocked, the operation just above described for bringing the door to its 30 seat, is reversed, thereby moving the threaded segments of the door and doorway out of engagement with each other, after which the door may be thrown open by grasping the handle 27 and moving said door outward on 35 the hinges 7. The axis of the worm 16 is in direct alignment with the hinges 7 so that the worm segment 14 remains in engagement with the worm at all times, whether the door is open or closed.

40 I claim:

1. The combination with a safe having a circular doorway, of a circular door, a hinged arm carrying a pivot on which the door is directly journaled at its center, interlocking 45 means on the door and within the doorway movable into and out of engagement by a

partial rotation of the door, and means for partially rotating the door comprising a worm segment carried by the door, a worm mounted on the safe, a hand-lever, and ratchet mechanism associated with said hand-lever and worm, substantially as described. 50

2. The combination with a safe having a circular doorway, of a circular door, a hinged 55 arm mounted on the safe and carrying a pin or pivot on which the door is directly journaled at its center, interlocking means on the door and within the doorway adapted to be thrown into and out of engagement by a partial rotation of the door, and means for partially rotating the door comprising a worm segment on the door, a worm mounted on the safe, a ratchet wheel on said worm, a hand-lever, and a reversible dog carried by said 60 hand-lever and coöperating with the ratchet wheel, substantially as described. 65

3. The combination with a safe having a circular doorway, of a circular door fitting the same, a hinged arm connected to the 70 safe and carrying a pivot on which said door is directly journaled at its center, interlocking means on the door and within the doorway movable into and out of engagement by a partial rotation of the door, and means for partially rotating the door comprising a worm segment carried by the door, a worm 75 mounted on the safe, a ratchet wheel connected with said worm, a fulcrum pin for said worm having an angular extension, a hand-lever fulcrumed on said extension, and a dog carried by said hand-lever and movable into and out of engagement with the ratchet wheel and adapted to turn the worm 80 in either direction. 85

In testimony whereof I affix my signature in presence of two witnesses.

EDWARD PASCOE.
